SYNCHRONIZING CONTROL

George Forrest Drake, Rockford, Ill., assignor to
 Woodward Governor Company, Rockford, Ill.,
 a corporation of Illinois

Application January 2, 1941, Serial No. 372,939

16 Claims. (Cl. 60—97)

This invention relates to a control by which the speed of one or more power units may be matched with that of another or master power unit.

The general object is to provide a speed matching control of the above character which is simple and inexpensive in construction, light in weight, operable over a wide speed range, and adapted for adjustment from a remote point of control.

Another object is to provide a novel means for effecting manual adjustment of the speed of a plurality of power units within a comparatively wide range and automatic synchronizing of the slave unit within a comparatively narrow range.

A further object is to provide such a speed matching control combined with means to indicate when the slave unit is adjusted for operation at a predetermined point within its automatic speed range.

The invention also resides in the novel construction of the control which facilitates carrying out of the foregoing objects.

Other objects and advantages of the invention will become apparent from the following detailed description taken in connection with the accompanying drawings, in which

Figure 1 is a schematic view and wiring diagram of a synchronizing control embodying the present invention.

Fig. 2 is a plan section taken along the line 2—2 of Fig. 4.

Figs. 3 and 4 are sections taken along the lines 3—3 and 4—4 of Fig. 2.

Fig. 5 is a section taken along the line 5—5 of Fig. 3.

Fig. 6 is a schematic view and wiring diagram showing the application of the invention to more than two power units.

While the improved synchronizing system is applicable to the control of various kinds of multiple unit power generators under widely varying operating conditions, it is especially adapted for and will be described herein as applied to the synchronization of a group of internal combustion engines. It is to be understood, however, that I do not intend to limit the invention by such disclosure nor to the particular construction of the governor and power units but aim to cover all modifications, alternative constructions and uses falling within the spirit and scope of the invention as expressed in the appended claims.

As illustrated in the two unit control shown in Fig. 1, the invention provides for individual manual adjustment of master and slave engines M and S for operation at any desired speed, and for automatic adjustment of the slave unit speed to

match the selected speed of the master unit. The speeds of the engines M and S are controlled by individual governors 10 and 11. These may operate directly on the engine throttles or, when the engine is arranged to drive an aircraft propeller as shown, the engine speed may be controlled by adjusting the propeller pitch. In the latter case, hydraulic pressure controlled by the governor is applied to a servo motor 12 which actuates a cam 13 by which the pitch of the propeller 14 is changed.

The governors are of similar construction each including a head 15 on the upper end of a sleeve 16 which rotates in a bore 17 of a hollow casing 18. Flyballs in the form of bell-cranks 19 are pivoted at 20 on the head and have arms bearing upwardly against the outer race of an anti-friction bearing 21, the inner race of which fits on a valve rod 22 and is urged downwardly by a coiled speeder spring 23 acting on a collar 24 fast on the upper end of the rod. Through a suitable gear connection 25, the lower end of the sleeve 16 is driven from the crankshaft 26 of the associated engine.

The valve rod 22 has a land 27 which cooperates with ports 28 in the sleeve 16 to control the flow of pressure fluid through a conduit 29 to the forward end of the servomotor, the rear end of which is connected by a pipe 29^a to the engine lubricating system and therefore maintained under pressure by the usual pump 29^b. Fluid is drawn from the engine lubricating system by a booster pump 30 and delivered at an increased pressure to the valve chamber above the land 27, the delivery pressure being maintained constant by a spring loaded by-pass valve 31.

With this arrangement, the hydraulic pressure applied to the servomotor will be varied in accordance with the position of the valve stem, which position is determined by the speed of the engine and the adjustment of the speeder spring 23. An increase in engine speed raises the pilot valve member permitting the flow of fluid from the head end of the servo cylinder and into the rod end resulting in an increase in the propeller pitch. Conversely, a decrease in speed below the governor setting results in the admission of pressure fluid to the head end of the servo cylinder and a consequent decrease in propeller pitch.

To provide for manual adjustment of the governor speed setting, the upper end of each speeder spring bears against a ring 32 threaded into a sleeve 33 which is slidable in a bore 34 in the cover 35 of the casing 18. The sleeve is formed with rack teeth 36 meshing with the pinion 37

fast on a shaft 38 which projects outwardly from the governor casing and carries a pulley 39 around which is wrapped a cable 40 extending to an operating lever 41 at the main control station. A coiled compression spring 46 is interposed between the ring 32 and a block 45 seated in the upper part of the cover. This spring counteracts the speeder spring 23 and prevents the latter from moving the adjusting mechanism to the lowest speed setting in the event of breakage of the cable 40.

age of the cable 40. The apparatus thus far described is typical of that now in common use for maintaining constant speed operation of airplane engines and for selecting different speed settings for the individual engines. The present invention contemplates an auxiliary adjustment by means of which the speed setting of one engine, S in this instance, may be varied automatically over a narrow range whereby the speed of this slave engine may be matched with that of the master engine M. To this end, a secondary independently adjustable speed spring 42 is incorporated in the governor of the slave engine to supplement the action of the main spring 23. Herein, the spring 42 is a coiled spring concentric and disposed within the spring 23 with its lower end threaded onto the upper end 43 of the valve rod 22. The upper end is threaded onto and thereby fastened to the lower end of a rack bar 44 slideable in the block 45 endwise along the axis of the valve stem. The teeth of the rack mesh with a pinion 47 on a shaft 48 journaled in the casing and rotatable to adjust the rack endwise and thereby vary the compressive or tensile stress exerted by the spring 42. The rack movement is limited in opposite directions by suitable means such as the end 49 of the casing cover and by engagement of a lug 50 on the rack with the block 45.

block 40. Automatic adjustment of the spring 42 is effected by a motor 51 housed in the casing cover 35. The motor is a so-called differential Selsyn comprising a stationary two pole three phase stator 52 and a three phase two pole rotor 53 excited from independent sources of three phase alternating current which produce rotating fields in both the rotor and the stator. The rotor is fast on a shaft 54 of an associated commutator switch 55. Through a pinion 56 and a gear 57, the torque of the motor is amplified and applied to the shaft 48. Thus, when the stator and rotor windings are energized at different frequencies, the motor will operate in a corresponding direction to raise or lower the rack 44 and thus extend or compress the spring 42 so long as the speed difference persists or until one of the limit stops is encountered.

To compare their speeds, the engines M and S are equipped with small permanent magnet generators 58 and 59 each driven from the crank-shaft 26 of its associated engine. The generators may be of the type disclosed in Patent No. 2,071,536 and are arranged for connection respectively with the stator and rotor windings of the differential motor 51. For this purpose, the terminals of the generators are extended to the stator and rotor windings respectively through conductors 60 and 61 having interposed therein a multiple pole single throw switch 62 adapted for manual operation from the same point of control as the speed adjusting levers 41.

When the switch 62 is closed, the synchronizing control will be operative. If the engines are operating at the same speeds, the frequencies of

the two alternating current sources will be identical and there will be no mechanical movement of the motor shaft 48. When the speeds are different, the frequencies of the generated currents will vary proportionately and the differential shaft will turn at a rate proportional to the difference in frequency and in a direction determined by which frequency is greater. The auxiliary spring 42 of the governor 11 is thus adjusted to change the speed of the setting and thereby bring the engine S back into synchronism with the master engine.

15 nism with the master engine.
It will be observed that the spring 42 may act
in compression or in tension and thus add or
subtract its force and that of the main speeder
spring. The characteristics of the springs are
such that the speed adjustment may be varied
over a major portion of the range by means of
the main spring 23 and over only a fraction of
the range, for example ten per cent, by adjust-
20 ment of the spring 42. In any case, this latter
range, although comparatively narrow, is suffi-
cient to enable normal deviations of the slave
engine speed from that of the master engine to
be corrected.

25 be corrected. In order to equalize the speed deviations of the slave engine that may be corrected for on each side of the speed of the master engine, means is provided for indicating when, by preliminary manual adjustment of the main spring 23 before the automatic control is operative, the stress in the spring 42 is zero and the speed settings of the two governors are identical, that is, the auxiliary spring stress is zero. As herein shown, this means comprises an electric signal lamp 63 responsive to movement of the adjuster for the spring 42 and arranged to be lighted when the adjuster is at the middle of its range of movement. This is accomplished by a cam 30 actuated switch 64 interposed in a conductor 65 which connects the ungrounded contact 66 of the switch to the lamp, which preferably is located at the remote point of control adjacent the levers 41. As shown, the insulated switch 35 contact is on an arm 67 pivoted at 68 within the governor casing. The arm overlaps and is urged by a spring 69 toward an insulating disk 70 and a smaller metal disk 71 both fast on the shaft 48 so that the metal disk is grounded. The operation of the synchronizing control above described in the normal flight of an airplane will be as follows. The take off is made with the switch 62 open and the engines under the manual control of their individual speed adjusting levers 41. When cruising speed has been attained, the switch 62 is closed rendering the motor 51 operative. If, at this time, the speed of the slave engine is, for example, somewhat below that of the master engine, the differential motor will, due to the lower frequency of the current generated by the slave engine, be energized to turn the shaft 48 counter-clockwise

compressing the spring 42 to its limit thereby adding to the force of the main spring 23 and effecting an increase in the speed setting of the slave engine governor. As the speed setting of the main spring continues to increase under manual control and the cumulative setting due to the combined action of the two springs exceeds that of the master engine, the operation of the differential motor will be reversed decreasing the compression of the auxiliary spring 42 progressively to compensate for increases in the manual setting of the slave engine governor. During this action, the speed of the slave engine will be slightly above that of the master depending on the rate at which the manual adjustment is effected. Finally, when the stress of the main spring has been increased manually to a value corresponding to speed setting of the master governor spring, the stress of the auxiliary spring will have been eliminated. At this point, the flat side of the insulating cam 70 will be presented to the switch contact 66 and the latter will move into contact with the disk 71 closing the switch 64 and lighting the lamp 63.

The signal advises the pilot that the automatic governor adjuster is now in the middle of its operating range and thus conditioned to correct for equal deviations of the slave engine speed in opposite directions from that of the master.

It will be observed that reverse action of the motor 51 will take place if the speed of the slave engine is above that of the master as the time the synchronizing control is rendered operative. In such a case, the rack bar 44 would be raised, thus placing the spring 42 under tension which decreases progressively as the speed setting of the manual adjuster is decreased. When effect of the spring 42 has been eliminated, the light signal is effective, thereby indicating that the automatic control is conditioned for proper operation. If, with the control thus conditioned, the speed of the slave engine falls below that of the master, the resulting frequency difference causes operation of the motor 51 in a direction to raise the rack 44 and thereby place the spring 42 under tension. This force subtracts from that of the spring 23 thereby increasing the speed setting of the governor until the speed of the slave engine again equals that of the master. The speed of the slave engine is changed in the same way in response to speed differences resulting from changes in the speed of the master engine relative to that of the slave unit. By varying the tension in the spring 42, the automatic control is capable of compensating automatically for speed decreases below that of the master up to one-half of the total range of adjustment determined by the characteristics of the auxiliary spring.

Assuming now that the speed of the slave engine rises above that of the master, reverse adjustment of the auxiliary spring will take place. That is, the motor 51 will turn in the opposite direction to lower the rack 44 and place the spring 42 under compression. This force is added to that of the main spring 23 decreasing the slave engine speed until this has matched that of the master.

The synchronizing control is, of course, disabled preparatory to landing. If this is done when the signal lamp 63 is lighted, the adjustor for the auxiliary spring will remain at the center of its range while the slave engine is on manual control. Then, if the two engines are synchro-

nized by manual adjustment before again shifting to automatic control, the manual adjustment of the slave engine as above described to light the lamp will be unnecessary.

5 The automatic synchronizing control as above described is especially adapted for use with two power units and on airplanes because the equipment required is reduced to a minimum. It will be observed that all of the parts are of light weight and comparatively inexpensive in construction and yet are extremely reliable in operation. The control is operable over the entire speed range of the controlled power units and may easily be rendered operative and inoperative at will.

If desired, the number of power units controlled may be increased and all or any number of these made selectable as the master. Fig. 6 shows a system applied to four engines A, B, C and D having two units B and C either one of which may be selected as the master, the other then being a slave unit. The control is generally similar to the two motor system previously described except for an increased capacity of the generators 59^b and 59^c of the master engines and the addition of manually operable two position switches 80 and 81 for determining which of the engines B or C shall act as the master. Also, since each master unit may operate as a slave unit, their governors are equipped with differential motors and auxiliary springs 42 adjusted by such motors.

Referring now to Fig. 6 in which the indicating lamps 63 and the manual switches therefor are omitted, the capacity of the alternators 59^b and 59^c for the units B and C is made sufficient, triple in the present instance, to energize one winding of the differential motors 51 of each of the three engines which it may serve as master. Each differential motor may be disabled by opening a manually operable switch 62 and the associated engine withdrawn from the automatic control. Manually operable switches 82 are provided in the conductors leading from the master generators 59^b and 59^c for interrupting or resuming the automatic control for all of the engines.

The selector switches 80 and 81 have a common two position actuator 83 which when positioned as shown conditions the circuits for operation of the engine C as the master. Thus, the output from the alternator 59^c is delivered through conductors 84 to the rotors of the motors 51^a, 51^b and 51^d and both windings of the motor 51^c are disconnected. Through the switch 80, the conductors 84 are connected to the rotor 53^b and the stator 52^b is energized by the alternator 59^b. As a result, the stators of the slave engines A, B and D are energized from the associated alternators while the rotors are excited by the master alternator. The operation is as previously described, the speed of each slave unit being matched automatically with that of the master. The automatic control for all of the slave engines may be disabled simply by opening the switch 82^c.

To make engine B the master, the switch actuator 83 is shifted to its other position. This disconnects both windings of the master motor 51^b, connects the alternator 59^b to the conductors 84 and conditions the motor 59^c for energization of its rotor and stator from the alternators 59^b and 59^c respectively. With the control thus conditioned, the speeds of the slave units A, C and

D are adjusted automatically to match that of the master unit B.

It will of course be apparent that provision may be made for using only one of the engines as the master. Or with appropriate changes in the switches, the number of engines selectable as the master may be increased.

I claim as my invention:

1. A control for matching the speed of one power unit with that of a master unit having, in combination, an adjustable governor controlling the speed of said master unit, a second adjustable governor controlling the speed of said second unit including two individually operable speed adjusting means coacting cumulatively to determine the governor speed setting, manually operable means controlling the adjustment of one of said adjusting means, electromagnetic means controlled selectively in accordance with differences between the speeds of said units, means actuated by said electromagnetic means to actuate said other adjusting means, and means to indicate the position of said second adjusting means approximately midway between the limits of its operating range.

2. A control for matching the speed of one power unit with that of a master unit having, in combination, a governor controlling the speed of said first mentioned unit including two individually adjustable speeder springs coacting to determine the governor speed setting, manually operable means controlling the adjustment of one of said springs, electric motor means variably energized in accordance with differences in the speeds of said units, means actuated by said motor means to adjust the stress of said second spring, and means for indicating the adjustment of said second spring approximately midway between the limits of its stress range.

3. A control for matching the speed of one power unit with that of a master unit having, in combination, a governor controlling the speed of said first mentioned unit including two individually adjustable speeder springs coacting cumulatively to determine the governor speed setting, manually operable means controlling the adjustment of one of said springs, electromagnetic means variably energized in accordance with differences in the speeds of said units, means actuated by said electromagnetic means to adjust the stress of said second spring, a switch actuated by said last mentioned means when said second spring is adjusted to a predetermined degree, and indicating means controlled by said switch.

4. A control for matching the speed of one power unit with that of a master unit having, in combination, manually adjustable means controlling the speed of said master unit, means including two individually adjustable springs coacting to determine, according to their combined stresses, the speed of the other unit, manually operable means controlling the adjustment of one of said springs, electromagnetic means differentially operable in accordance with the speed of said master unit, means actuated by said electromagnetic means to adjust the stress of said second spring, and means actuated in unison with speed changes of said second spring and operable to indicate a predetermined adjustment of the latter.

5. A control for matching the speed of one power unit with that of a master unit having, in combination, a governor controlling the speed of said first mentioned unit including two individu-

ally adjustable speed adjusting means coacting to determine the governor speed setting, manually operable means controlling the adjustment of one of said adjusting means, means automatically operable to actuate the other adjusting means and correct for differences in the speeds of said units, and means operable to indicate a predetermined speed setting of said automatic means irrespective of the setting of said manually operable means.

6. In a synchronizing control, a governor having two independently movable speed adjusting means coacting cumulatively to determine the governor speed setting, and means operable to indicate the position of one of said adjusting means at a predetermined point in its operating range irrespective of the adjustment of the other means.

7. In a synchronizing control, a governor having two independently movable speed adjusting means coacting cumulatively to determine the governor speed setting, automatically operable means for actuating one of said adjusting means, and means operable automatically to indicate a predetermined speed setting of said last mentioned means irrespective of the adjustment of the other means.

8. In a synchronizing control, a governor having two independently movable speed adjusting means coacting cumulatively to determine the governor speed setting, automatically operable means for actuating one of said adjusting means, and means operable automatically to indicate the setting of said last mentioned means substantially midway between the limits of its operating range irrespective of the setting of the other adjusting means.

9. In a synchronizing control, the combination of a governor automatically controlling the speed of a power unit and having rotary flyballs, two coiled springs concentrically arranged and operable cumulatively to counteract the action of said flyballs, one of said springs being maintained under compression, manually operable means for variably loading said last mentioned means, the other of said springs acting in tension or compression, and means operable automatically to vary the character and degree of stress in said other spring selectively.

10. In a synchronizing control, a governor having a manually adjustable main speeder spring, and an auxiliary speeder spring selectively adjustable to add to or subtract from the force of said first spring whereby the speed setting of the governor is determined by the cumulative loading of the two springs.

11. In a synchronizing control, a governor having a coiled speeder spring adjustable to vary the governor speed setting, a second coiled spring coacting with said first spring to determine the speed setting, and means operable selectively to place said second spring under tension or compression.

12. In a centrifugal speed governor having a movable control member and centrifugal weights operatively associated with said control member, two speeder springs of different strength acting in parallel on said control members to oppose the action of said centrifugal weights thereon, respective movable abutments for said springs movable independently of each other, and respective means independent of each other for moving said abutments, the weaker of said springs being connected to its movable abutment and

to said control member to act on the control member in compression or in tension.

13. In a control for matching the speed of two prime movers, the combination of a governor on one prime mover having rotary flyballs, a speeder spring acting on said flyballs and adjustable selectively to vary the governor speed setting, a secondary governor adjusting member movable independently of said spring, an auxiliary single coil spring in parallel with said first spring producing a force variable selectively by movement of said member and arranged to add to or subtract from the force of the first spring or to exert substantially no force either on said adjusting member or on said flyballs when the member is in a neutral position, and power means adapted to be deenergized to permit free movement of said adjusting member or to be energized selectively in accordance with the speeds of said prime movers and cause movement of said member in one direction or the other away from said neutral position while permitting of movement of the member to such position when the power means is deenergized.

14. In a control for matching the speed of one prime mover against that of a master prime mover, the combination of a governor controlling the speed of said first mentioned prime mover and having rotary centrifugal weights, first and second adjusting members movable independently of each other, resilient means adjustable by said first adjusting member and normally exerting a force opposing the action of said weights to determine the governor speed setting, a reversible electric motor responsive to differences between the speeds of said prime movers and operable to adjust the position of said second member, and auxiliary resilient means acting between said weights and said second adjusting member and exerting substantially no force on said weights when the member is in one position, whereby the governor speed setting is then determined by the setting of said first adjusting member, said auxiliary resilient means being op-

erable by movement of the second member in opposite directions from said neutral position to respectively increase and decrease the total resilient force on said weights.

15. In a control for matching the speeds of two prime movers each having a governor with rotary flyballs and a speeder spring acting thereon and selectively adjustable to vary the governor speed setting, the combination of a rotary differential motor energized selectively in accordance with the speeds of both of said motors, a second spring associated with one of said governors and acting on the flyballs thereof in parallel with the speeder spring, means providing a driving connection between said motor and said second spring whereby the latter is stressed differentially either to add to or subtract from the governor speed setting when the speeds of the two prime movers differ, said second spring having a neutral position in which substantially no supplemental force is exerted either on said connection or on the flyballs of its governor whereby the speed settings of both governors are determined solely by the adjustments of these individual speeder springs.

16. In a control for matching the speeds of two prime movers, the combination of a governor for one of said prime movers having rotary flyweights and a main speed adjuster exerting a resilient force on said weights, an auxiliary independently movable speed adjusting member, power means operable to move said member in opposite directions from a neutral position in response to rises and falls in the speed of one prime mover relative to that of the other, and a spring comprising a single resilient coil connected between said member and said flyweights and adapted to be placed either under tension or compression to exert oppositely acting forces on said flyweights, the character of said spring stress being determined by the direction of movement of said member away from said neutral position.

GEORGE FORREST DRAKE.
